UNITED STATES PATENT OFFICE.

ALBERT E. DOMAN, OF ELBRIDGE, NEW YORK, ASSIGNOR, BY MESNE ASSIGNMENTS,
TO DYNETO ELECTRIC CORPORATION, OF SYRACUSE, NEW YORK, A CORPORATION
OF NEW YORK.

BRUSH UNIT.

1,272,637.

Specification of Letters Patent. Patented July 16, 1918.

Application filed June 8, 1916. Serial No. 102,490.

To all whom it may concern:

Be it known that I, ALBERT E. DOMAN, a citizen of the United States, and resident of Elbridge, in the county of Onondaga, in the State of New York, have invented new and useful Improvements in Brush Units, of which the following, taken in connection with the accompanying drawings, is a full, clear, and exact description.

10 This invention relates to certain improvements in brush units particularly adapted for use in electrical apparatus, such as dynamo electric machines, motors, motor generators, and the like, and has a particular application to such electrical apparatus as is used in connection with starting and lighting systems for automobiles and the like.

An object of the invention is to produce a one piece brush-carrying unit of molded insulating material which can be economically manufactured and which cannot be improperly assembled or put out of adjustment, and eliminating entirely the possibility of corrosion tending to lock the brushes 25 in their holders, and of short circuits apt to occur with metallic brush holders.

A further object is to shape the unit in segmental form so that it can be readily removed as a whole from the assemblage as it 30 could not be if it inclosed the shaft.

A further object is to prevent turning or spinning of the brushes, particularly the center or third brushes, and to assure their insertion in the holder in proper position by 35 forming them of rectangular shape and permitting their independent operation by spacing them and their controlling springs with a metal insert.

Another object relates to the ready re-40 movability of all the brushes from the unit, and to the construction of the main brush springs in such manner that they will retain the brushes in retracted position in their holders if desired.

45 Other objects and advantages will appear in the following description, taken in connection with the accompanying drawings, in which—

Figure 1 is an inverted elevation of the 50 unit.

Fig. 2 is a top plan view of the same.

Fig. 3 is a cross section on line 3—3, Fig. 2.

Fig. 4 is a section on line 4—4, Fig. 2.

Fig. 5 is a section on line 5—5, Fig. 1.

Fig. 6 is a section on line 6—6, Fig. 1.

55

The invention comprises, in combination with a dynamo electric or similar machine, a segmental molded brush unit formed of fibrous or other non-frangible insulating material embodying preferably a flat segmental base —1—, and in this instance three up-standing radially disposed tubular brush holders —2—, —3— and —4—, respectively. The holders —2— and —4— are adapted to slidably receive and guide the main brushes 60 —5— and —6—, each of said holders having its vertical walls at the rear provided with alined recesses —9— and —10— in which springs —7— and —8—, respectively, are adapted to move following the brushes 65 —5— and —6—, respectively, as they are worn away.

These main brushes may be retracted in their holders and held in that position as shown in dotted lines Fig. 2, by the springs 75 —7— and —8— if desired. These main springs may be shaped as shown, and have one end secured to and are coiled about posts —11—. The posts —11— are formed with tubular ends —12— externally threaded for 80 engagement with bosses —13— formed on and integral with the base —1— and internally threaded for coaction with said post. The tubular ends of posts —11— are also internally threaded for engagement with 85 threaded screws —14— having insulating washers —15— mounted thereon for suitable engagement with an insulating plate —16—, all of which parts are secured together by the threaded engagement of said posts and 90 screws.

Suitable conductors, as wires —17— and —18—, are secured to each of brushes —5— and —6— beneath the washer or head —19— of a tubular eyelet or rivet passed 95 through and counter-sunk in opposite sides of the brushes and permanently secured to said brushes, and these conductors preferably lie in diagonally disposed channels —21— and —22— in said brushes and have 100 their opposite ends electrically connected to binding posts —23— adjustably engaged

with the base —1— and the binding posts —23— in turn are connected to the main leads —24—.

The holder —3— is provided with a horizontal partition or insert —25— dividing it into a pair of rectangular guideways for receiving the brush springs —26— and —27— and the brushes —28— and —29— of rectangular form to fit the guideways. The springs —26— and —27— bear at the rear against a removable metallic cap or cap plate —30— which serves as a connection for the brush holder lead —31—, and preferably the cap is provided with a pair of open-sided slots —32— and —33— in which suitable headed pins —34— and —35—, adjustably secured to the holder —3—, are adapted to slide.

Although I have shown and described a particular construction and arrangement of the parts in accomplishing the objects of this invention, I do not desire to limit myself to any particular construction, number, shape or formation of parts, as many changes may be made in the details of each of the same without departing from the spirit of this invention as set forth in the appended claims.

What I claim is:

30 1. In a dynamo electric machine, a brush unit comprising a molded insulating base, having a central upstanding tubular flange, a pair of brushes in said tubular flange, means for separating the said brushes, separate springs for moving said brushes inwardly, a removable cap for holding the springs in operative position, said molded base provided with additional upstanding tubular flanges arranged respectively upon 40 opposite sides of said central flange, a brush arranged in each of said additional flanges and spring means for holding said brushes in operative position.

45 2. In a device of the class described a brush unit formed of a single piece of insulating material and comprising a base formed with a plurality of upstanding brush-holders provided with substantially radial bores, said base provided with hollow 50 bosses at opposite sides of said brush-holders, posts secured in said hollow bosses and spring bars having one of their ends secured to said posts and their other ends positioned at the rear of oppositely disposed brush-holders, 55 respectively.

55 3. In a brush-holder unit a segmental molded insulating base having integral therewith a series of upstanding tubular brush-holders and hollow bosses positioned 60 at opposite sides of said brush-holders and projecting upwardly from said base.

4. A brush-holder unit comprising a one-piece segmental insulating base having inte-

gral therewith a tubular upstanding brush-holder, and hollow bosses positioned at opposite sides of said brush-holder and projecting upwardly from said base.

5. A brush unit comprising a one-piece segmental insulating base embodying a plurality of tubular brush-holders, brushes in said brush-holders, posts mounted on the insulating base, and springs mounted on said posts and bearing against the brushes, respectively.

6. In a dynamo electric machine, a brush unit comprising a one-piece insulating base having a central upstanding hollow brush-holder, said base provided with additional integral upstanding tubular brush-holders arranged, respectively, upon opposite sides 80 of said central brush-holder, a brush arranged in each of said brush-holders, and separate spring means for holding each of said brushes in operative position.

7. In a dynamo electric machine, a brush unit comprising a one-piece insulating base having a central upstanding hollow brush-holder, said base provided with additional integral upstanding tubular brush-holders arranged, respectively, upon opposite sides 90 of said central brush-holder, a brush arranged in each of said brush-holders, said base provided with integral hollow bosses at opposite sides of said additional brush-holders and upon opposite sides of the central 95 brush-holder, posts mounted in said bosses, a spring mounted on each post and having portions in contact with the respective brushes arranged in said additional brush-holders.

100 8. In a dynamo electric machine, a brush unit comprising a one-piece insulating base having a central upstanding hollow brush-holder, said base provided with additional integral upstanding tubular brush-holders 105 arranged, respectively, upon opposite sides of said central brush-holder, a brush arranged in each of said brush-holders, said base provided with integral hollow bosses at opposite sides of said additional brush-holders and upon opposite sides of the central 110 brush-holder, posts mounted in said bosses, a spring mounted on each post and having portions in contact with the respective brushes arranged in said additional brush-holders, respectively, a plate in contact with said insulating base, and screws extending through 115 said plate through the insulating base and engaged with said posts.

9. In a dynamo electric machine, a brush 120 unit comprising an insulating base embodying a plurality of brush-holders, posts mounted on said base, springs mounted on said posts for holding the brushes in operative position, an insulating plate in 125 contact with said base, said plate pro-

vided with depressions alined with said posts, screws extending through said depressions in the plate through the insulating base and engaged with said posts, respectively, and insulating washers on said screws having portions adapted to fit within the depressions in said plate.

In witness whereof I have hereunto set my hand this 3rd day of June, 1916.

ALBERT E. DOMAN.
